UNITED STATES PATENT OFFICE.

OVILA J. BERGERON, OF MANCHESTER, NEW HAMPSHIRE.

COLLAR BUTTON.

Application filed August 24, 1927. Serial No. 215,180.

This invention relates to new and useful improvements in buttons, and particularly to collar buttons.

One object of the present invention is to provide a button which will not pull out of the button-hole of the shirt band, or of the collar.

Another object is to provide a button of this character which is adapted for use in connection with button-holes, of the bands of shirts, which have become so torn that the ordinary headed-shank button will not remain therein.

Other objects and advantages will be apparent from the following description when taken in connection with the accompanying drawing.

In the drawing:

Figure 1 is a perspective view of one form of button used at the rear of the shirt band, the latter dotted.

Figure 2 is a perspective view of a modification of the button for the rear of the collar band of the shirt.

Figure 3 is a view, similar to Figure 1, showing the form of button used in the holes of the front of the collar band of the shirt.

Figure 4 is a perspective view of a modification of the front button.

Referring to the accompanying drawing, and particularly to Figure 1, the button for the rear button-hole of the collar band 10, includes a longitudinally curved flat bar portion 11, which is adapted to be disposed in the pocket beneath the rear button-hole of the collar band, and longitudinally thereof, the curvature of such bar being adapted to fit the curvature of the neck of the wearer. Extending at right angles from the ends of the bar 11, and in parallel relation to each other, and in a common direction, are the tabs 12, such tabs being bent, intermediate their lengths, as shown in Figure 1, for the reception of the lower edge of the rear wall of said button-hole pocket. From the center of the same edge of the bar 11, from which the tabs 12 extend, there extends an L-shaped tab 13, the intermediate portion of the shank of which is bent so that the transverse leg 14, is offset with respect to the

body of the bar, whereby to facilitate the insertion of such tab in the rear button-hole of a collar. Thus, when the device is properly disposed on the collar band of a shirt, the L-shaped tab 13 will project through the 55 button-hole of the band, while the tabs 12 will embrace the lower edge of the rear wall of the pocket of the button-hole. It will be particularly noted that the horizontal leg of the tab 13 extends toward the left, as 60 viewed from the rear of the collar band, so that the pull of the collar will be toward the right, and the said tab positively held from disengagement from the button-hole.

In Figure 2 there is shown a modification 65 of the button, wherein the central tab 15 is provided with a disk-like head 16, as distinguished from the head of the tab 13.

The form of the front button, shown in Figure 3, comprises the transverse bar 17, 70 having the stem or shank of a button upset in one end thereof, said button shank being disposed through one of the front button-holes of the collar band of the shirt. From one edge of the other end of the bar 75 17 there extends a tab 18, similar in form to the tabs 12, and being similarly rebent to embrace a portion of the upper edge of the neck or collar band of the shirt.

In Figure 4 there is shown a modification 80 of the front button, wherein each end of the bar 17 is provided with a tab 18, such tabs being bent and embracing the upper edge of the collar band, at opposite sides of the button shank, at the ends of the button-hole. 85

What is claimed is:

As an article of manufacture, a collar-button comprising a bar having a tongue extending from one of the longer edges of the bar at an angle to the plane of the bar, and 90 elongated tongues extending from the opposite ends of said edge of the bar and being doubled intermediate their lengths to extend transversely of the end portions of said bar, the doubled portions of said tongues extending beyond the said edge of the bar. 95

In testimony whereof, I affix my signature.

OVILA J. BERGERON.
